UNITED STATES PATENT OFFICE.

DAVID J. BISSELL, JR., OF SPOKANE, WASHINGTON, ASSIGNOR TO OTIS AUTOMATIC TRAIN CONTROL INCORPORATED, OF SPOKANE, WASHINGTON, A CORPORATION OF WASHINGTON.

RAMP DEVICE FOR AUTOMATIC TRAIN-CONTROL APPARATUS.

Application filed May 1, 1923. Serial No. 635,900.

To all whom it may concern:

- Be it known that I, DAVID J. BISSELL, Jr., a citizen of the United States, and resident of Spokane, in the county of Spokane and 5 State of Washington, have invented certain new and useful Improvements in Ramp Devices for Automatic Train-Control Apparatus, of which the following is a specification.
- 10 My invention relates to track mechanism for automatic train control apparatus, and has particular reference to an improved ramp device as and for the purpose set forth in my copending application serially numbered 15 635,895.

In the accompanying drawings which are 20 illustrative of my improvements in a preferred form and wherein like characters of reference denote corresponding parts in the different views—

Figure 1 is a side elevation of a ramp device embodying the novel and essential features of my invention;

Figure 2, a longitudinal section there- 25 through; and

Figure 3, a transverse section on the line 3—3 of Figure 2.

Referring to the drawings in detail, it 30 will be observed that my improved ramp device consists of an elongated, substantially rectangular casing 10 to one end of which is pivoted, as at 11, the outer extremity of a ramp rail 12, which ramp rail, at its inner end, is pivoted as at 13, to the inner end of 35 a second ramp rail 14 that, at its outer extremity, rests upon a roller 15 or is directly slidably engaged with the other end of the casing, as may be desired. Thus said ramp rails are capable of being depressed and ele- 40 vated with respect to the casing as is manifest.

Within the casing 10 is a lever 16 that is intermediately pivoted as at 17, and weight- 45 ed at one end as at 18, whereby a roller 19 on its other end is held normally in contact with one of the ramp rails and said rails as a result held normally elevated. By this arrangement it is manifest that upon downward movement of that end of the lever 16 carrying roller 19, the influence of weight 18 upon the ramp rails is removed and said rails as a result will assume a horizontal position under the influence of gravity.

Within the casing 10 is mounted a sole- 55 noid 20, the core 21 of which is connected with lever 16 as indicated at 22, while the field thereof has leading thereto from without the casing, conductors 23, 24. In one of 60 said conductors, herein shown as conductor 23, is a switch 25 that is maintained open by the weight 18 on lever 16 when said lever is in its normal position shown in Figure 2 holding the ramp rails elevated, but that is 65 adapted to close automatically when the weight is raised a relatively slight distance as is manifest. Also arranged in one of said 70 conductors is another switch 26 that is closed normally, but that is so controlled by a float device 27 that in the event of an excess quantity of water collecting within the casing, 75 it will automatically open. Conductors 23, 24 lead to switch devices of any preferred type (not shown) operable by the usual 80 block signals, so that when a given signal is set at "stop" or "caution" position, the circuit through said conductors to its related ramp device or devices will be deenergized, and when the signal is in "clear" position, the circuit will be energized.

In view of the foregoing, the operation of 85 my improved ramp device is apparent and as follows: When a given block or zone of trackage is clear and the usual signals so indicate that fact, the circuit through conductors 23, 24, although energized, is main- 90 tained broken by switch 25 and the ramp rails are maintained elevated by weight 18. Upon contact of the shoe of a ramp valve with one of the ramp rails, however, with resultant slight depression of the ramp rails and lifting of weight 18, said switch will 95 close and the solenoid field will become energized, thus retracting the core 21 and allowing the ramp rails to fall by gravity to horizontal position whereby the shoe of the ramp valve will be unaffected. The circuit will then remain closed until deenergized by movement of a signal to "stop" or "caution" position, following which the ramp rails will assume their normal elevated position. 100 On the other hand, if the signal controlling a given ramp device is set at "stop" position, the circuit through the solenoid field will be deenergized and the resistance of weight 18 to downward movement of the 105 ramp rails will result in said rails remaining

23
elevated, so that when the shoe of a ramp valve strikes the same, consequent actuation of such ramp valve will result.

From the foregoing description considered 5 in connection with the accompanying drawings, it is believed that the construction, operation and advantages of my improved ramp valve will be clearly understood. It is desired to point out, however, that various 10 changes and desirable additions may be made in and to the same within the spirit and scope of my invention as defined in the appended claims.

I claim:—

- 15 1. A ramp device for automatic train control apparatus, including a projectable and depressible ramp rail, weight operated means to project said ramp rail, electrical means to hold said weight operated means ineffective to project said ramp rail, electric 20 conductors leading to said electrical means, and a switch in one of said conductors held open by said weight operated means in a projected position of said ramp rail.
- 25 2. A ramp device for automatic train control apparatus including a projectable and depressible ramp rail, an intermediately pivoted lever weighted at one end and at its other end carrying a roller adapted to contact with said ramp rail to maintain the latter normally projected, electrical means 30 to hold said weight operated means ineffec-

tive to project said ramp rail, and an automatically closable switch held open by said weight operated means in the normal position of the latter, said switch being effective to control the operation of said electrical means. 35

3. A ramp device for automatic train control apparatus including a casing, a projectable and retractable ramp rail carried by said casing, weight operated means to project said ramp rail, electrical means to hold said weight operated means ineffective to project said ramp rail, electrical conductors 40 leading to said electrical means, and a float controlled normally closed switch in one of said conductors. 45

4. A ramp device for automatic train control apparatus including a casing, a ramp rail carried by said casing movable to active and inactive positions, weight operated means to move said ramp rail to active position, electrical means to hold said weight operated means ineffective to hold said ramp rail in active position, electrical conductors 50 leading to said electrical means, a normally closed switch in one of said conductors, and means automatically operable upon collection of a predetermined amount of water 55 within said casing to open said switch. 60

In testimony whereof I hereunto affix my signature.

DAVID J. BISSELL, JR.
